by Mark Blum, Attorney

UNITED STATES PATENT OFFICE.

LOUIS AUGUSTE NEVIÈRE, OF TOURS, FRANCE, ASSIGNOR TO AMERICAN LIGHTER CORPORATION, OF NEW YORK, N. Y., A CORPORATION OF NEW YORK.

POCKET LIGHTER.

Application filed December 21, 1925, Serial No. 76,878, and in Belgium December 22, 1924.

This invention relates to so-called pocket lighters and has as its object to remedy certain defects in apparatus of this type as previously constructed.

5 One of the objects of this invention is to simplify the fuel reservoir construction so as to make the refilling elements more compact and less liable to damage.

10 Another object of this invention is to provide means for equalizing the wear on the ferro-cerium igniting element.

Another object of this invention is to provide means for extinguishing the ignited wick when the apparatus is closed so as to 15 prevent oxidation of the casing immediately above the wick portion.

Another object of this invention is to provide means for protecting those parts of the walls of the lighter which are heated by 20 the wick from oxidation.

Another object of my invention is to provide a mechanism whereby certain of the parts can be manipulated or adjusted while the device is either in the operative or in the 25 inoperative position.

Other objects of this invention will appear in the following description and drawings which illustrate preferred embodiments of 30 my invention. Fig. 1 is a perspective view of the fuel containing element and shows the closure therefor in open position. Fig. 2 is a longitudinal section showing the opening and closing devices, the special wick cover and the special mounting for the ferro-cerium element. Fig. 3 is a section similar 35 to that shown in Fig. 2 but with the device shown in operative instead of in its inoperative position. Fig. 4 is a section of a device similar to that shown in Fig. 2 but embodying a modified form of cover or cap for the wick portion. Fig. 5 is a section taken on 40 the line A—A of Fig. 4 and showing a special construction for preventing oxidation of the walls of the lighter in the vicinity of the wick. Fig. 6 is a transverse section showing 45 the holder for the ferro-cerium igniting element, and the special means for revolving it about its longitudinal axis.

Referring to the several figures of the 50 drawing, 1 designates a cartridge containing

a fuel compartment 10, a wick 3 dipping into said fuel compartment, and a holder 4 for the ferro-cerium element. A friction element 9 is adapted to press against the ferro-cerium igniter, said friction element being 55 rotated by means of the gear 22. A hinged cover 25 is provided for the wick and air holes 19 in the side walls of the cartridge and situated at approximately the wick level, are provided for furnishing air to the wick. 60

The cartridge 1, including all the elements contained therein and attached thereto, is adapted to fit telescopically into a shell 2, forming the assembly shown in Figs. 2, 3, 4 and 5. A spring 8 is located between the 65 end of the cartridge 1 and the inner portion of shell 2 and this spring 8 urges the cartridge 1 out of the shell 2. The outward movement of cartridge 1 is limited by a stop 17. Shell 2 and cartridge 1 have semi-circular recesses 30 and 31 formed in their upper portions so that when the two sections are moved into the position shown in Fig. 3, said recesses 30 and 31 are aligned and provide an opening through which the flame 70 from the wick may emerge. Shell 2 is provided with a rack 40 adapted to mesh at one side thereof with pinion 22. 75

The special construction for filling the fuel compartment 10 in cartridge 1 is shown 80 in Fig. 1. Referring to this figure, it will be seen that a hinged door or closure 18 is provided, which fits snugly into the end of the cartridge 1. For filling the fuel compartment it is only necessary to extract the 85 cartridge 1 from the assembly in a manner which will be described later and to pour the fuel into the compartment 10 through the door 18. It will be noted from Figs. 2, 3 and 4 that when the cartridge 1 is in assembled position that spring 8 presses against the closure 18 and keeps it closed. 90

Means for insuring equal wear of the ferro-cerium element are shown in Fig. 6. Referring to this figure, it will be seen that 95 the igniting element 50 has a square contour and that it is pressed upwardly by spring 51. This spring 51 is enclosed in a rotatable sleeve 52 and sleeve 52 fits into an outer shell 4 which is rigidly attached to cartridge 100

1. When the ferro-cerium igniting element becomes worn on one side it is only necessary to manipulate the element 11 to rotate sleeve 52 in shell 4 to expose a new portion of the igniting element. The inner surface sleeve 52 has a square cross-section at the point where it receives the pyrophoric alloy.

The special hinged cover for extinguishing the flame of the wick is shown in Figs. 2, 10 3 and 4. In the modification shown in Figs. 2 and 3, the cap 25 is shown hinged to a pin 26 connected to the side walls of cartridge 1. A spring 27 is provided and this urges the cap 25 to turn upwardly on its 15 pin 26. When the device is in the position shown in Fig. 3, it will be seen that the cap 25 swings clear of the cartridge 1 and the shell 2. When the device moves into the position shown in Fig. 2, the movement of 20 cartridge 1 in shell 2 forces the cap 25 back to enclose the wick. A lug 28 of sufficient length is provided on cap 25 to force the cap 25 down so that it fits snugly onto the wick.

In the modification shown in Fig. 4, the 25 cap 25' is hinged at 26' and it is raised from the wick when the shell 2 is pressed against the pin 29, the horizontal movement of the pin producing an upward turning motion of the cap 25' by means of the lever 32 and the 30 hinge 26'. The cap 25' is brought back to its closed position by means of the spring 33 which urges the pin 29 to the right.

Figures 4 and 5 show the improved means provided for preventing oxidation of the 35 walls of the lighter adjacent the wick. Referring to these figures, it will be seen that a U shaped piece of sheet metal 60 is provided which fits snugly between the upper walls of cartridge 1, and is interposed 40 between the wick and the lateral walls of the cartridge. The legs of the piece of metal 60 U are curved inwardly (see Fig. 5) and they are stamped out to provide an ar- 45 cuate opening 61 (see Fig. 4). The air for the flame enters through the holes 19 in the walls of the cartridge 1, and it passes to the wick through the openings 61 and it also ascends (see Fig. 5) through passages 62 formed by the concave portions of pro- 50 tecting element 60 and the permanent walls of the cartridge 1. The air ascending through passages 62 serves to cool the protecting element 60 and also serves to prevent the transmission of heat from the protecting 55 element to the walls of the cartridge. When the protecting element becomes oxidized it can be slipped out and a new one may be introduced.

The mode of operating the device will 60 now be described. Assuming the lighter to be in the inoperative position shown in Fig. 2, cartridge 1 is pressed so as to move into shell 2 against the action of spring 8. As cartridge 1 moves inwardly, rack 40 rotates

pinion 22 and friction element 9 rubbing 65 against the pyrophoric element 50 produces a spark. At the same time the recess 30 in cartridge 1 is moved so as to coincide with orifice 31 in shell 2, and air holes 19 on cartridge 1 come into alignment with air 70 ports 20 (see Fig. 4) in the side walls of shell 2. Air for the flame is thus provided and an outlet for the flame is also provided. As the orifices 30 and 31 begin to come into 75 alignment, the opening at the top of the lighter is gradually uncovered and cap 25 (or 25') under the action of the spring 27 (or in the modification shown in Fig. 4, under the action of pin 29) swings clear of 80 the wick. Since the uncapping of the wick begins as soon as the cartridge 1 is forced 85 into its shell 2, there is ample time for the sparking element to ignite the wick. The flame thus produced rises between the protecting walls of the element 60 and emerges through the opening in the top of the lighter. When the pyrophoric alloy becomes used on one side, element 11 is rotated to provide a fresh surface. To extinguish the 90 lighter it is only necessary to release the pressure on cartridge 1. The spring 8 then moves the cartridge out of the shell 2 until the stop 17 prevents further movement of the cartridge causing the capping to fit onto the wick and to extinguish the flame. 95 The various elements then assume the positions shown in Fig. 2.

When it is necessary to refill the fuel compartment, stop 17, which is turned upward at a small angle from the plate 16 (see Fig. 100 1) is forced inwardly while the apparatus is in the position shown in Figs. 2 or 4. The two telescoping sections may then be separated and the refilling operation may be performed. The plate 16 is secured to 105 the body cartridge 1, by a small rivet 80.

It is to be understood that the invention is not limited to the particular constructional embodiments which have been more particularly described but that all modifications are included falling within a fair interpretation of the claims.

What I claim is:

1. An automatic lighter comprising a cartridge having a fuel container and a wick 115 associated with said fuel container, the said cartridge having the exterior thereof provided with air inlets located below the top of said wick and auxiliary concave walls located between the wick and the said cartridge. 120

2. A device according to claim 1 in which the said auxiliary walls are open adjacent the bottom thereof to enable air to pass from the said air inlets to the wick.

3. An automatic lighter comprising a cartridge having main lateral walls provided with air inlets, a wick located between said

walls and associated with a source of fuel, auxiliary concave walls located between said wick and the lateral walls of the cartridge, said auxiliary walls having openings below 5 said wick to enable air to pass from said air inlets to the said wick.

4. An auxiliary protecting member for

automatic lighters comprising a U-shaped member having concave legs, said legs being provided with openings at the bottom portion thereof. 10

In testimony whereof I have signed my name to this specification.

LOUIS AUGUSTE NEVIÈRE.
